(57) **CLAIM**

The ornamental design for a folding camping chair, as shown and described.

DESCRIPTION

FIG. 1 is a perspective view of a folding camping chair showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any shading and cross-hatching are not features of the design but are utilized to illustrate the surface contours of the folding camping chair design in the drawings.

The broken lines shown in the drawings depict stitching which forms part of the claimed design.
